UNITED STATES PATENT OFFICE.

CHARLES W. LOKEY, OF BIRMINGHAM, ALABAMA.

FASTENING FOR REMOVABLE DENTAL BRIDGES AND BRIDGE-PLATES.

1,299,364.

Specification of Letters Patent.

Patented Apr. 1, 1919.

Application filed July 16, 1917. Serial No. 180,702.

To all whom it may concern:

Be it known that I, CHARLES W. LOKEY, a citizen of the United States of America, residing at Birmingham, in the county of 5 Jefferson and State of Alabama, have invented certain new and useful Improvements in Fastenings for Removable Dental Bridges and Bridge-Plates, of which the following is a specification.

10 My invention relates to fastenings for removable dental bridges and bridge plates which will permit the abutment tooth to which the bridge or plate is fastened, to have a free normal movement during mastication 15 without straining or breaking the joint between the fastening elements or their respective connections to the abutment and bridge or bridge plate.

My present invention is more especially 20 intended as an improvement on the type of dental fastening described in Letters Patent of the United States No. 1,193,034, issued to me on the 16th day of August, 1916, and which comprises a keeper, formed of hard 25 metal shaped to provide side grooves and preferably a top groove alining with the side grooves, and an anchor attachment for the removable bridge or bridge plate, which is formed of bent wire (preferably drawn 30 wire of hard metal such as iridio platinum) that is shaped to fit snugly into the grooves of the keeper and to interlock firmly therewith so that the fastening resists with much 35 strength any relative movement between the keeper and anchor except in the direction in which the bridge or bridge plate is moved to detach it from the abutment.

According to my present invention the web of the keeper and the sides of the anchor which engage it are so shaped as to permit a limited rocking play to take care of the normal movement between keeper and anchor in a transverse plane through the joint. Provision for this play can be made by making the web of the keeper in transverse cross-section elliptic or wider at its center than at its ends, and leaving the sides of the anchor that engage the keeper straight, or the same play may be obtained where the 50 sides of the web are straight and provision for the rocking play is made in the shape of the parts of the anchor which engage the web.

My present invention further contemplates contracting the anchor by slightly drawing 55 or bending in either or both sides thereof near the neck so that it will snap over the thicker central portion of an elliptic keeper web and securely prevent accidental disconnection of the fastening elements without, 60 however, interfering with the limited play that makes provision for normal movements of the bridge or the abutment tooth.

A further object of my invention is to improve the construction of the keeper proper 65 by tapering its end next to the gum so that it is inclined away from the gum. This arrangement will prevent food collecting between the keeper and gum and make it easier to keep the parts clean. 70

My invention further comprises the novel details of construction and arrangements of parts which in their preferred embodiments only are illustrated in the accompanying drawings which form a part of this 75 specification, and in which:—

Figure 1 is a plan view illustrating the lower jaw with a bridge plate attached by my improved fastening and partly broken away. 80

Fig. 2 is a perspective view of the anchor and keeper detached, the keeper being shown attached to a tooth or abutment.

Fig. 3 is an enlarged sectional view through the abutment showing the assembled 85 anchor and keeper in side elevation.

Fig. 4 is a view showing the anchor in front elevation mounted in a bridge or bridge plate.

Fig. 5 is an enlarged vertical sectional 90 view taken on the line 5—5 of Fig. 3, with the anchor shown in elevation.

Fig. 6 is a view similar to Fig. 5 of a modification of my invention in which the sides of the web are straight and the anchor loop 95 enlarged to provide for the rocking play desired.

Similar reference numerals refer to similar parts throughout the drawings.

In the embodiment of my invention illustrated, a detachable bridge plate is adapted to be attached to abutments 1 which may be of any suitable construction and attached to any desired natural teeth as may be best suited for each individual case. To 105 each abutment I solder or otherwise attach

a keeper which is formed of a block of hard metal having a flat front face 2 which is connected by an integral shank or web 3 with a back face 4 which is preferably thinner than the front face and adapted to be soldered to the abutment. The web, which is formed by the side grooves in the keeper, is preferably cut away below the top or outer end edge of the keeper so as to form a top groove or seat for the anchor. The web, as shown in Figs. 1 to 5, is made thicker at or slightly below its center (see Fig. 5) and it is tapered or made thinner toward its top and bottom ends so as to give it in vertical cross section what may be termed generally an elliptic shape. The inner end of the keeper adjacent to the gum is beveled away from the abutment and gum as indicated by the outwardly sloping face 5.

20 The bridge plate 6 has firmly embedded therein an anchor, preferably formed of drawn wire or hard metal. It comprises ends 7 which are rigidly embedded in the rubber saddle of the bridge plate or they 25 may be rigidly attached in any other suitable manner to a metal saddle or to the bridge or bridge plate. The wire is bent upwardly to form a loop portion 8, the bases of the sides of which are bent outwardly 30 and horizontally at 9 to join the ends 7 which lie in a plane at right angles to that of the loop. The sides of the loop, as shown in Fig. 2, are straight and correspond to the construction shown in Fig. 8 of my Letters 35 Patent hereinbefore referred to, as such form can be used with my improved keeper, but I prefer to contract the neck of the anchor loop by drawing in its sides as at 10 (Figs. 4 and 5). It is preferable that both 40 sides of the loop be thus drawn in but not essential as a snap lock could be obtained by contracting the neck of the loop in any manner.

From a consideration of Fig. 5 it will be 45 apparent that when the keeper and anchor loop are interlocked, the keeper is free to rock in the anchor within predetermined limits in either direction, as indicated by the arrow, and thus allow for the normal 50 play or movement of the abutment tooth during mastication, and it is conversely true that the bridge plate itself can have a like limited play by the rocking of the anchor loop about the keeper web which is sufficient to prevent an unnatural strain on the 55 abutment during hard biting. It is desirable that the keeper and anchor should have only that limited relative rocking movement which will take care of the natural relative 60 movements between the bridge and the abutment in chewing, as a joint which would permit too much relative play between the keeper and the anchor would prove an unsatisfactory fastening for a bridge or bridge

plate. By contracting the neck of the loop 65 it will snap into place about the keeper web and can only be disengaged by a strong pull upwardly or downwardly according to whether the bridge is carried by the upper or lower jaw. In Fig. 6 I show the keeper 70 web 11 formed with parallel sides and the top 12 of the anchor loop is struck on an arc from the center of the web and made as wide as is necessary to provide for the rocking play desired. The sides of the loop 75 are bent in at 13 to engage the sides of the web and are then bent out away from the sides thus forming side bearings which will permit the keeper and anchor to rock 80 relatively.

The essential feature of my invention is that the keeper and anchor be designed to permit only sufficient relative rocking movements to avoid undue strains on the fastenings or abutments that would otherwise result from normal tooth movements during 85 mastication.

Having thus described my invention, what I claim as new and desire to secure by Letters Patent, is:—

90 1. In a dental fastening, in combination, a keeper having a head and a vertically elongated shank which tapers in width toward one end, and an anchor having sides which straddle the shank behind the head 95 and clamp between them the widest portion thereof, clearance being left between the sides and narrow end of the shank to permit only a limited rocking movement of the shank in the anchor and of the anchor on 100 the shank.

2. In a dental fastening, in combination, a keeper having side grooves, and an anchor adapted to straddle the keeper and engage it to prevent both downward and lateral 105 play in the joint, there being a clearance provided above and below the points of contact between the sides of the keeper and the anchor to permit only a predetermined relative rocking movement in the joint between the anchor and keeper, as and for the 110 purposes described.

3. In a dental fastening, in combination, a keeper having opposite side grooves which leave between them a substantially elliptical shaped web disposed with its long axis vertical, and an anchor formed of bent wire having closely spaced side members adapted to be received in said grooves and in normal position to yieldingly engage the said 115 web only opposite its short axis.

4. In a dental fastening, a keeper formed of an elongated body of hard metal having in its opposite side faces longitudinal grooves which shape the body into front and back walls connected by a longitudinal and relatively narrow central web which tapers toward both end edges of the keeper. 125

5. In a dental fastening, an anchor formed of hard metal wire having a portion thereof adapted for attachment to the bridge or bridge plate, and having portions thereof spaced from said attachment portion and bent at an angle thereto into closely spaced parallelism to form a clasp eye for engage-

ment with a keeper, one of the sides of said eye being bent to contract its end adjacent to the bridge or bridge plate.

10

In testimony whereof I affix my signature.

CHARLES W. LOKEY.
